US00D587117S

(12) **United States Design Patent**
Crawford

(10) **Patent No.:** **US D587,117 S**
(45) **Date of Patent:** **** Feb. 24, 2009**

(54) **CONTAINER AND CLOSURE**

(75) Inventor: **John C. Crawford**, Mahopac, NY (US)

(73) Assignee: **Colgate-Palmolive Company**, New York, NY (US)

(**) Term: **14 Years**

(21) Appl. No.: **29/317,752**

(22) Filed: **May 6, 2008**

(51) **LOC (9) Cl.** 09-01

(52) **U.S. Cl.** **D9/504**

(58) **Field of Classification Search** D9/500, D9/502-505, 516, 519, 529, 530, 537, 539, D9/545, 549, 558, 682, 686, 688-691; D7/598, D7/608; 215/379, 381-382; 220/660, 662, 220/669-672, 675

See application file for complete search history.

(57) **CLAIM**

The ornamental design for a container and closure, as shown and described.

DESCRIPTION

FIG. 1 is a perspective view of the container and closure of my design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof; and,

FIG. 7 is a bottom plan view thereof.

The broken lines in the drawings showing the bottom surface of the container illustrates a portion of the design that forms no part of the claim.

1 Claim, 6 Drawing Sheets
